MINING MACHINE

Joseph F. Joy and Clyde P. Baldwin, Claremont,
N. H., assignors to Sullivan Machinery Com-
pany, a corporation of Massachusetts

Application July 15, 1936, Serial No. 90,744

15 Claims. (Cl. 74—389)

This invention relates to mining machines and more particularly, but not exclusively, to improvements in coal mining machines of the flexibly fed, floor cutter type.

5 An object of this invention is to provide an improved coal mining machine having improved features of construction whereby the kerf cutting means may be operated and controlled in an improved and more effective manner. An 10 other object is to provide an improved coal mining machine of the flexibly fed, floor cutter type having improved means for feeding and guiding the machine during the cutting operation. A further object is to provide an improved coal 15 mining machine of the combined room and pillar and longwall type whereby the machine may operate in accordance with either the room and pillar or longwall system of mining. Still another object is to provide an improved coal mining machine of the flexibly fed, floor cutter type wherein relatively rotatable feed operating and controlling members respectively adapted to cooperate with flexible feeding and controlling elements, are employed for feeding and guiding 20 the machine, and having improved means for driving and controlling the feed operating and controlling members. A still further object is to provide an improved mining machine transmission mechanism which is extremely compact, 25 and whereby the feed operating and controlling members may be driven in an improved manner. These and other objects and advantages of the invention will, however, hereinafter more fully appear.

30 In the accompanying drawings, there are shown for purposes of illustration several forms which the invention may assume in practice.

In these drawings—

Fig. 1 is a plan view of one illustrative embodiment of the improved mining machine, a portion of the casing being broken away to illustrate details of construction;

Fig. 2 is a side elevational view of the machine shown in Fig. 1;

Fig. 19 is a cross sectional view taken substantially on line 19—19 of Fig. 11;

Fig. 20 is a diagrammatic view showing the hydraulic fluid system and the associated control means;

Figs. 21 and 22 are views similar to Figs. 1 and 2, respectively, showing a further modified form of construction;

Fig. 23 is an enlarged view in longitudinal vertical section taken substantially on line 23—23 of Fig. 21;

Fig. 24 is an end elevational view of the machine shown in Figs. 21 and 22;

Fig. 25 is a detail vertical sectional view taken substantially on line 25—25 of Fig. 21;

Fig. 26 is an enlarged cross sectional view taken substantially on line 26—26 of Fig. 21;

Fig. 27 is a detail view in longitudinal vertical section taken substantially on line 27—27 of Fig. 21.

In the several embodiments of the invention, there is shown a coal mining machine of the combined room and pillar and longwall, flexibly fed, floor cutter type, although it will be evident

that various features of the invention may be incorporated in mining machines of various other types.

In the illustrative embodiment of the invention disclosed in Figs. 1 to 10, inclusive, the mining machine generally comprises a casing 1 of low, compact, generally rectangular shape having a smooth bottom surface 2 and adapted to rest upon and slide in any direction over the mine floor. The machine casing 1 comprises a feed and cutter frame section 3, a motor frame section 4 and a control and guide frame section 5, and the casing sections are rigidly united in any suitable manner. Arranged within a transverse horizontal chamber 6, extending across the lower portion of the casing section 3 at one end of the motor casing section, are relatively rotatable feed operating and controlling members, herein in the form of cable winding drums 7 and 8 having respectively wound thereon feeding and controlling cables 9 and 18, while projecting horizontally from the machine casing 1 is an elongated, horizontal plane kerf cutter 11.

Now referring to the improved driving means for the kerf cutter, it will be noted that arranged within the motor casing 4 is a motor, herein preferably of the reversible electric type, having its power shaft 12 horizontally disposed and extending longitudinally of the machine, with its axis of rotation lying in the central longitudinal vertical plane of the machine. Formed integral with the motor power shaft, at one end of the motor, is a spur motor pinion 13 meshing with a spur gear 14 (see Fig. 4) keyed to a horizontal longitudinally extending shaft 15. The shaft 15 is arranged parallel with and in horizontal planes above the motor power shaft and suitably journaled within the casing section 3. Keyed to and driven by the shaft 15 is a bevel gear 16 meshing with a horizontal bevel gear 17 having its hub journaled on bearing sleeves supported by a clutch sleeve 18 keyed to a vertical shaft 19. As illustrated, the casing section 3 is provided, at one end thereof, with a projecting bearing frame 20 and gear housing 29 of partially cylindrical shape providing a housing for the bevel gears 16, 17, and the vertical shaft 19 is journaled on this frame portion 20. The upper portion of the frame portion 20 is provided with an upstanding circular bearing support 21, while depending from the lower portion of the frame portion is a circular bearing support 22, and the shaft 19 is journaled in ball bearings arranged within these bearing supports in the manner shown in Fig. 4. Formed on the hub of the bevel gear 17 are clutch teeth 23 connectible, by a sliding clutch member 24, to clutch teeth 25 formed on the clutch sleeve 18. The sliding clutch member 24 is operated by a shipper yoke 26 mounted on a longitudinal shaft 27 journaled in the casing section 3 and having an arm 28 connected by a link 29 to a crank 30 fixed to an operating rod 31. As shown in Fig. 1, this operating rod extends longitudinally of the machine casing along one side thereof and has fixed thereto, at its opposite end, an operating lever 32 so that the clutch may be controlled from the operator's station at the end of the machine remote from the kerf cutter. Keyed to the vertical shaft 19 and driven thereby is a chain sprocket 33 engaging and driving an endless cutter chain 34 mounted for circulation about the margin of a cutter bar 35 of the kerf cutter. It will thus be seen that when the sliding clutch 24 is connected, the cutter chain 34 may be driven from the motor power shaft 12

through the spur gearing 13, 14, shaft 15, bevel gearing 16, 17 and the vertical shaft 19; and, when the clutch 24 is disconnected, the cutter chain may remain idle during running of the motor.

The pivotal mounting for the cutter bar 35 for supporting the latter for swinging movement about a pivotal axis coincident with the axis of the cutter drive shaft 19 comprises a hanger frame 36 having a cylindrical bearing portion 37 journaled on a bearing sleeve supported by the cylindrical bearing support 22. Formed integral with the hanger frame is an upstanding frame portion 38 having secured thereto a bearing frame 39 overlying the upper portion of the frame portion 20 of the casing section 3 and journaled on bearing sleeves supported by the circular bearing support 21. It will thus be seen that the cutter bar has a pair of spaced bearing supports on the machine casing, resulting in an extremely stable pivotal mounting for the cutter bar.

Now referring to the improved flexible feeding and guiding means, and more particularly to the driving means therefor, it will be noted that keyed to and driven by the longitudinal cutter drive shaft 15 is a worm 46 meshing, at its opposite sides, with horizontal worm wheels 41 and 42, herein arranged on parallel vertical axes lying in a vertical plane extending transversely of the machine and spaced equidistantly from a longitudinal vertical plane including the axis of rotation of the shaft 15. The chamber 6, within which the cable winding drums are arranged, lies in a transverse zone between the motor and the kerf cutter, and these drums are arranged on parallel vertical axes aligned with the axes of the worm wheels 41 and 42, respectively. Rotatable with and driven by the worm wheels 41 and 42, respectively, are spur gears 43 and 44 meshing with spur gears 45 and 46, herein arranged on vertical axes spaced equidistantly from a longitudinal vertical plane including the axis of rotation of the shaft 15 and parallel with the worm wheel axes. The hubs 47 of the spur gears 45 and 46 are connectible by conventional multiple disc clutches 48 and 49, respectively, to aligned vertical shafts 50 and 51. Rotatable with and driven by these vertical shafts are spur gears 52 and 53 meshing with spur gears 54 and 55, herein arranged coaxially with the worm wheels 41 and 42, respectively, in horizontal planes below the latter, as clearly shown in Fig. 7. The worm wheels 41 and 42 are connectible by conventional multiple disc clutches 56 and 57, respectively, to the upstanding hubs 58 of the spur gears 54 and 55. The hubs of the worm wheels and the spur gears are journaled on ball bearings supported by vertical shafts 59 and 60 arranged coaxially with the worm wheels respectively, these shafts being threadedly secured at 61, at their upper ends within the top of the casing section 3, and fixed at their lower ends at 62, within cylindrical bearing supports 63 formed integral with the bottom of the casing section. Formed on the bottoms of the spur gears 54, 55 are clutch teeth 64 connectible by sliding clutch members 65 to clutch teeth 66 formed on the cable winding drums 7 and 8, respectively, so that when these clutches are connected the drums may be driven by either the worm wheels 41 or the spur gears. The worm wheels 41 and 42 constitute the high speed terminal driving elements for the drums, while the spur gears 54 and 55 constitute the low speed terminal driving elements; and, when the friction clutches 48 and 49

are applied and the clutches 56 and 57 released, the drums may be driven in cable winding direction at a relatively low speed appropriate for cutting; and, when the clutches 48 and 49 are released and the clutches 56 and 57 applied, the drums may be driven in cable winding direction through the worm wheels at a relatively high machine haulage speed. As shown in Fig. 7, each of the cable winding drums has, at its upper side, 10 a sleeve-like hub 61 journaled in roller bearings 68 supported within a bearing hub 69 formed integral with the casing section 3, while the lower sides of the drums are journaled on roller bearings 70 supported by the bearing support 63. 15 Each drum is supported by a thrust ring 71 on the bearing hub 69 (see Fig. 7), and a packing 72 provides a lubricant and dust seal for the lower drum bearing 70, while a similar packing 73 provides a lubricant and dust seal for the upper drum bearing 68.

In this instance, a retarding friction or brake is provided for each cable winding drum so that rotation of the drums in unwinding direction may be frictionally resisted when the drums are disconnected from their driving means; and these retarding frictions comprise, as shown in Fig. 8, spur gears 75 and 76 meshing with the spur gears 54 and 55 respectively, and rotated by the latter. These spur gears 75 and 76 are formed integral with vertical shafts 77 and 78 journaled in ball bearings suitably journaled in the casing section 3; and keyed to the upper portions of each of these shafts is a series of frictional braking discs 79 interleaved with a series 30 of frictional braking discs 80 keyed to a cylindrical bearing support 81 within which the upper ball bearings for the shafts are supported. Circular plates 82 having projections 83 engageable with the upper non-rotatable discs are provided for pressing the interleaved discs together, thereby to frictionally retard rotation of the spur gears meshing with the spur gears 54 and 55. The means for operating the clutch applying plate 82 will be presently described. The locking means for locking the kerf cutter in its different adjusted positions about its pivot comprises, as shown most clearly in Fig. 8, a vertical cylinder 85 supported at 86 within a bore in the casing section 3 and containing a reciprocable piston 87. Secured to the piston 87 is a locking pin 88 adapted to project in one of a series of locking apertures 89 formed in the hanger frame 36 for the cutter bar 35. Threaded at 90 on the upper end of the cylinder 85 is a cap 91 having a chamber within which is arranged a coil spring 92 acting on the upper surface of the piston 87 for urging the locking pin 88 towards its locking position. A packing 93 embraces the locking pin 88 for providing a seal between the cylinder bore 94 at the lower side of the piston and the movable locking pin. Hydraulic pressure may be supplied to the cylinder bore at the lower side of the piston 87 to move the piston upwardly against the tension of the coil spring 92, thereby to release the locking pin from the locking aperture in the cutter bar hanger frame in a manner to be later described.

Now referring to the improved hydraulic control means for the various friction clutches, the drum release clutches, the retarding frictions and the kerf cutter lock, it will be noted that supported on the casing section 5 is a valve box 95 having horizontal bores containing rotary control valves 96, 97, 98, 99, 100 and 101. Formed within the casing section 5 is a lubricant reser-

voir 102 having mounted therein a hydraulic pump 103, preferably of the intermeshing gear type and driven from the rear end of the motor power shaft 12; the pump having its discharge side connected through a conduit 104 to the supply passage 105 of the valve box. The discharge passage 106 of the valve box is connected by a discharge conduit 107 back to reservoir 102. Referring more particularly to the operating means for the disc clutches 56 and 57, it will be noted that arranged within the upper portion of the casing section 3 are vertical bores 108 each containing a reciprocable plunger 109, these plungers each engaging the upper race 110 of a ball thrust bearing 111. The lower bearing races 112 engage vertical plungers 113 extending through openings in the worm wheels and, in turn, engaging, at their lower ends, pressure applying plates 114 for the discs of the clutches. Interposed between the worm wheel hubs and the lower thrust bearing races 112 and encircling the plungers 113 are coiled springs 115 for normally urging the plungers 109 toward their uppermost clutch releasing position. The upper ends of the bores containing the plungers 109 are connected, 25 through branched conduits 116, in turn connected through branched conduits 117 and 118, to the bores for the valves 96 and 100; and, when these valves are in the position shown in Fig. 10, hydraulic pressure may flow, through the conduit 104, supply passage 105, passages on the valves 96 and 100, the conduits 117 and 118 to the branched conduits 116, and thence to the bores at the upper sides of the plungers 109; and as a result the latter are moved downwardly by the hydraulic pressure acting thereon, smoothly to apply a loading pressure to the discs of the friction clutches. The controlling means for the friction clutches 48 and 49 for the low speed terminal gears comprises, as shown in Fig. 8, an annular bores 119 each containing an annular plunger 120 engageable, through a ball thrust bearing 121, with vertical plungers 122 guided in openings in the spur gear and secured to a pressure applying ring 123 engaging the upper disc 40 of the clutch. The bores 119 at the upper sides of the plungers 120 are connected, through conduits 124 and 125 to the bores for the valves 96 and 100, so that, when the valves are in the position opposite from that shown in Fig. 10, hydraulic pressure may flow from the pump 103, through the conduit 104, supply passage 105, passage on the valves 96 and 100, and conduits 124 and 125 to act on the upper surfaces of the plungers 120 smoothly to load the discs of the clutches. It 45 will thus be seen that, when the fast speed clutches are applied, the slow speed clutches are always released, and vice versa. The control means for the retarding frictions comprises bores 126 containing plungers 127 engaging the upper 60 surfaces of the pressure applying plates 82. The bores at the upper sides of the plungers 127 are connected, through conduits 128 and 129, to the bore of the valve 98, so that, when the valve is in the position shown in Fig. 10, hydraulic pressure may flow through the conduit 104, supply passage 105, a passage on the valve 98 and conduit 129, to move the plunger 127 downwardly to apply the retarding friction for the spur gear 76, while the retarding friction for the spur gear 75 is connected to exhaust through conduit 128, a passage on the valve 98, discharge passage 106, and discharge conduit 107. When the position of the valve 98 is reversed, the retarding friction for the spur gear 76 is released, while the re- 75

tarding friction for the spur gear 73 is applied. The operating means for the drum release clutches 66 each comprise a cylinder 130 on which the clutch member 66 is mounted and containing a plunger 131. Secured to the plunger 131 are operating rods 132 engaging the upper race 133 of a ball thrust bearing 134, in turn engaging the lower bearing race 135 integral with the clutch member 66. The upper end of the bore of the cylinder 130 is packed by a packing member 136. Axial passages 137 formed in the shafts 59 and 60 respectively communicate, through radial passages 138, with the bores of the cylinders 130 at the upper sides of the plungers 131, so that, when hydraulic pressure is applied to the cylinder bores, the clutch members 66 are moved downwardly to release the clutch elements on the drums from the clutch elements on the gears 54 and 55 respectively. When the pressure is released from the cylinder bores at the upper sides of the plungers 131, coil springs 139, encircling the clutch members 66, move the latter upwardly into their clutched position. The passages 137 in the shafts are connected, through conduits 140, 141, to the bores for the valves 97 and 99, so that, when the valves are in the position shown in Fig. 10, hydraulic pressure may flow from the conduit 104, through supply passage 105, through passages on the valves 97 and 99 and through the conduits 140, 141, to move the plungers 131 downwardly to release the drum clutches 66. When the valves are turned into their position opposite from that shown in Fig. 10, the conduits 140 and 141 are connected to the discharge passage 106 so that the pressure acting on the plungers 131 is released and the drum clutches connected by the coil springs 138. The bar locking cylinder at the lower side of the plunger 87 is connected, through a conduit 142, to the bore for the valve 101, so that, when the valve is in the position shown in Fig. 10, hydraulic pressure may flow from the conduit 104, through discharge passage 105, a passage on the valve 101 and conduit 142, to the lower side of the plunger 87 to move the locking pin 88 into its released position. When the position of the valve 101 is reversed, the conduit 142 is connected to the discharge passage 106 so that the pressure below the plunger 87 is released and the locking pin 88 moved into its locking position by the coil spring 82. By closing the valve, the locking pin may be maintained in its released position. It will be noted that the conduit 142 has a flared end (see Fig. 6) engaged by the tapered end of a plug 141 held in position on the frame by a set screw 142', thereby to provide a fluid-tight point. This structure enables the removal of the top cover of the casing without disturbing the conduit 142. As shown in Fig. 9, arranged adjacent the control valves in the valve box is a by-pass control valve 143 having a manual operating plunger 144 so that the operator may readily control the pressure in the hydraulic system. It is accordingly evident that the fast and slow speed friction clutches, the retarding frictions, the drum release clutches and the bar lock are all hydraulically controlled, thereby facilitating the operation thereof, it being only necessary to rotate the control valves into the proper positions; and, due to the fact that the control valve levers are arranged in the rear end of the machine, it is possible to effect the control of the various devices of the machine at the operator's station 75 within his easy reach.

As previously mentioned, the cable winding drums 7 and 8 are arranged within the transverse chamber 6 in a transverse zone between the motor and the kerf cutter; and the cables 9 and 10 wound on these drums are adapted to be extended from the machine in various manners to effect maneuvering and feeding of the machine and to swing the kerf cutter about its pivot. Arranged on parallel vertical axes at the opposite sides of the casing section 3 are sets of horizontal guide rolls 145 and 146, these guide rolls being arranged at the opposite corners of the chamber 6, while journaled on the horizontal axes in coaxial relation, at the opposite sides of the casing section 5, are vertical guide rolls 147. Arranged at the rear of the guide rolls 147, are horizontal guide rolls 149 and 150, each mounted on a swingable bracket 151 pivoted on a vertical axis at 152. The brackets 151 are each engageable in their different positions with suitable stop lugs 153 on the casing section 5. Formed on the hanger frame 36 for the cutter bar is an arcuate cable guiding groove 154; and integral with the hanger frame, near the ends of the groove 154, are hook-shaped portions 155 to which eye members 156, fixed to the free ends of the cables, are connectable. Either of the cables may be extended from its winding drum about the guiding groove on the hanger frame into connection with a hook-shaped portion 155; and, when the bar lock 88 is released and the cable is wound in by its drum, the cutter bar may be swung about its pivot relative to the machine casing. One cable may be employed for effecting cutter bar swing in one direction and the other cable to effect cutter bar swing in the opposite direction. When the cutter bar is swung into the desired angular position with respect to the machine casing, it may be locked to the casing by the locking pin 88.

The general mode of operation of the improved mining machine is as follows: The cables may be extended in various directions from the machine about the guide rolls 145, 146, 147, 149 and 150. The cable 10 may be extended from the drum 8 rearwardly around the rear guide roll 145, around the vertical guide roll 147 and then forwardly along the side of the machine and about the guiding groove 154 on the hanger frame into connection with one of the hook-like members 155, so that, when the cable is wound in, the cutter bar may be swung about its pivot, and the cable 9 may be extended in a similar manner from the winding drum 7. Either of the cables may be extended from the winding drums 55 around the forward guiding rolls 145, 146, laterally from the sides of the machine to a suitable anchor jack located at the rib, so that, when the cable is wound in, the machine may be fed laterally across the coal face. Either of the cables may be extended from the drums rearwardly around the rear guide rolls 145, 146, beneath the guide rolls 147 and around the guide rolls 149 and 150 laterally from the rear end of the machine to a suitable anchor jack located at the 60 rib so that either cable may act as a guiding cable to control the angular position of the machine with respect to the coal face. The machine may be fed rapidly over the mine floor by either of the cables 9 and 10 under the control 70 of the high speed friction clutches 56 and 57, and may be fed over the mine floor during the cutting operation at a relatively slow cutting speed under the control of the low speed clutches 48, 49. When the high and low speed clutches 75

are released, the drums may rotate in unwinding direction under various degrees of frictional resistance regulated by the retarding frictions 79, 80. The operator, by manipulating the control levers of the various control valves, may regulate the supply of hydraulic pressure flowing to the control plungers for the various clutches, the retarding frictions and the cutter bar lock, so that the control, drum releasing and retarding frictions may be hydraulically applied and the cutter bar lock hydraulically released. The machine is of the combined room and pillar and longwall type, capable of operating in accordance with either the room and pillar or longwall system of mining, the cutter bar being sumped into the coal either by bodily moving the machine endwise or swinging the cutter bar, and the machine fed bodily along the coal face in the manner well understood by those skilled in the art. The machine is also reversible and may be operated to cut in either of opposite directions simply by reversing the motor, rearranging the cables on the drums and reversing the cutters of the cutter chain.

As previously mentioned, the flexible feeding and guiding means for the machine is similar to the form of the invention above described. Referring more particularly to the driving means for the feeding and guiding means, it will be noted that keyed to the end of the motor power shaft opposite from the bevel gear 172 is a spur pinion 209 meshing with a spur gear 210 keyed to a longitudinally extending shaft 211. The shaft 211 is arranged with its axis parallel with and in horizontal planes above the motor power shaft axis, and is suitably journaled within the feed frame section 164. Fixed to and driven by the shaft 211 is a worm 212 meshing, at its opposite sides, with horizontal worm wheels 213 and 214, herein arranged on parallel vertical axes lying in a vertical plane extending transversely of the machine and spaced equidistantly from a longitudinal vertical plane including the axis of rotation of the shaft 211. The cable winding drums 163 and 167 are arranged in the chamber 165 on parallel vertical axes alined with the axes of the worm wheels 213 and 214 respectively. Rotatable with and driven by the worm wheels 213 and 214, respectively, are spur gears 215 and 216 meshing with spur gears 217 and 218, herein arranged on vertical axes spaced equidistantly from a longitudinal vertical plane including the axis of rotation of the shaft 211 and parallel with the worm wheel axes. Driven by the spur gears 217 and 218, respectively, are spur gears 219 and 220 meshing with spur gears 221 and 222, respectively, herein arranged coaxially with the worm wheels. As in the form of the invention above described, the worm wheels constitute the high speed terminal driving elements for the cable winding drums, while the spur gears 221 and 222 constitute the low speed terminal driving gears for the drums, and these gears are connectible in driving relation with the drums by multiple disc clutches in the same manner as that disclosed in Figs. 7 and 8, and the winding drums are provided with similar drum release clutches. As a transverse section taken through the axes of the feed drums and the high and low speed terminal driving gears is substantially the same as the transverse section shown in Fig. 7, further description and illustration of this portion of the feeding mechanism is deemed unnecessary other than to state that the cable winding drums may be driven in winding direction at either a high

machine haulage speed or a low speed appropriate for cutting, under the control of the disc clutches. In this form of the invention, the retarding frictions or brakes 79, 80 are omitted although it will be evident that such retarding frictions may be readily incorporated in the feed gearing of this form of the invention.

Means is provided for tilting the machine to change the angle in altitude of the kerf cutter, comprising a pair of hydraulic jacks arranged at the opposite sides of the cutter frame section 162. These hydraulic jacks comprise cylinders 225 arranged in a substantially vertical position at the opposite sides of the cutter frame section 162 and rigidly secured to the latter. As shown in Fig. 19, these cylinders contain reciprocable pistons 226 having piston rods 227 extending downwardly through the packed bottom heads 228 of the cylinders. Fixed to the lower ends of the piston rods are shoes 229 engageable with the mine floor. It is evident that, when fluid pressure is supplied to the upper ends of the cylinders, at the upper sides of the pistons, the shoes 229 are moved into engagement with the mine floor and the cutter end of the machine is lifted from the floor, thereby tilting the cutter bar about a transverse axis. When fluid pressure is supplied to one or the other of these cylinders, the machine may be tilted about a longitudinal axis, thereby to tilt the cutter bar edgewise. The means for supplying hydraulic pressure to these hydraulic jacks will be later described.

In the illustrative embodiment of the invention shown in Figs. 11 to 20 inclusive, the feeding and cutting mechanisms are essentially the same as those described in the embodiment of the invention described above, with the exception that, in this instance, the motor is arranged intermediate the feeding and cutting mechanisms, and the cutting mechanism is driven from one end of the motor and the feeding mechanism from the opposite end thereof. This illustrative embodiment of the improved mining machine comprises a casing 160 of low, compact, generally rectangular shape having a smooth bottom surface 161 and adapted to rest upon and slide in any direction over the mine floor. The machine casing 160 comprises a cutter frame section 162, a motor frame section 163 and a feed frame section 164, the motor frame section 163 arranged intermediate the cutter and feed frame sections, and the casing sections are rigidly united in any suitable manner. Arranged within a transverse horizontal chamber 165 extending across the lower portion of the feed frame section 164 at the end of the machine remote from the cutting mechanism, are relatively rotatable feed operating and controlling members, herein in the form of cable winding drums 166 and 167 having respectively wound thereon feeding and controlling cables 168 and 169, while projecting horizontally from the machine casing 160 is an elongated, horizontal, plane kerf cutter 170.

The driving means for the kerf cutter is shown most clearly in Fig. 13. Arranged in the motor casing section 163 is a motor, herein preferably of the reversible electric type, having its power shaft 171 horizontally disposed and extending longitudinally of the machine with its axis of rotation lying in the central longitudinal vertical plane of the machine. Keyed to one end of the motor power shaft is a bevel gear 172 meshing with a bevel gear 173, herein formed integral with a vertical shaft 174. This shaft is suitably journaled within ball bearings supported within the

casing section 162 and has formed integral therewith and driven thereby a spur gear 175 meshing with a spur gear 176. The spur gear 176 has its hub 177 journaled on ball bearings supported by a vertical shaft 178. This shaft is journaled at its upper end within a ball bearing supported within an upstanding circular bearing support 179 integral with the casing section 162, while this shaft is journaled near its lower end within a roller bearing supported within a cylindrical bearing support 180 likewise formed integral with the casing section 162. Formed on the hub of the spur gear 176 are clutch teeth 181 connectible by a sliding clutch member 182 to clutch teeth 183 formed on a clutch member 184 keyed to the shaft 178. The sliding clutch member 182 is operated by a shipper yoke 188 mounted on a transverse shaft 189 rotatably supported within the casing section 162. Fixed to the shaft 189 is a lever 190 pivotally connected to a crank 191 secured to a transverse operating shaft 192 arranged parallel with the shaft 189. Fixed to the shaft 192 on the exterior of the machine casing is a lever 193; and connected to this lever is an operating cable 194 in the form of a wire rope secured to a flat operating bar 195 guided on and extending longitudinally over the tops of the casing sections 163 and 164 and in turn having secured thereto, at the end of the machine casing remote from the kerf cutter, a swiveled operating handle 196. When the handle 196 is grasped by the operator and the cable pulled rearwardly, the shipper yoke is swung to move the clutch member 182 upwardly into its connected position; and, when the handle 196 is released, the clutch member 182 drops downwardly into its disconnected position by gravity. The clutch is held in its connected position. It may be locked therein simply by swinging the handle 196 downwardly into engagement with the end of the machine casing so that the handle abuts the casing. Keyed at the lower end of the vertical shaft 178 and driven thereby is a chain sprocket 185 which engages and drives an endless cutter chain 186 guided for circulation about the margin of a cutter bar 187 of the kerf cutter. It will thus be seen that when the clutch 182 is connected the cutter chain 186 may be driven from the motor power shaft through the bevel gearing 172, 173, spur gears 175, 176 and the vertical shaft 178; and when the clutch is disconnected the cutter chain may remain idle during running of the motor.

The pivotal mounting for the kerf cutter is similar to that of the embodiment of the invention described above, and comprises a hanger frame 197 having a cylindrical bearing portion 198 journaled on a bearing sleeve supported by the cylindrical bearing support 180. Formed integral with the hanger frame is an upstanding frame portion 199 having secured thereto a bearing frame 200 overlying the upper portion of the casing section 162 and journaled on bearing sleeves supported by the circular bearing support 179. The cutter bar lock, for locking the cutter bar in its different angular positions about its pivotal mounting on the machine casing, is essentially the same as that disclosed in Fig. 8, and comprises, as shown in Fig. 18, a vertical cylinder 201 supported within the casing section 162 and containing a plunger 202 secured to a vertically reciprocable locking pin 203. This locking pin is adapted to enter any one of a series of locking apertures 204 formed in the cutter bar hanger frame 197 and is formed with an upper extension 205 guided within a bore of a guide member 206. Interposed between the

upper end of the bore of the guide member and the pin extension is a coil spring 207 for urging the locking pin toward its locking position. A packing 208 embraces the locking pin to provide a seal between the cylinder bore, at the lower side of the plunger, and the movable locking pin. When pressure fluid is supplied to the cylinder bore at the lower side of the plunger 202, the locking pin is moved upwardly against the tension of the coil spring into its released position. 5 10

Now referring to the improved hydraulic control means for the various friction clutches, the drum release clutches, the kerf cutter lock, and the machine tilting jacks, it will be noted that supported on the feed frame section 164 are valve boxes 231 and 232 having horizontal bores containing rotary control valves 233, 234, 235, 236, 237, 238 and 239, the valves 233, 234 and 235 arranged in the bores of the valve box 231 and the remaining valves arranged in the bores of the valve box 232. The chamber within the feed frame section, within which the feed driving gears are arranged, constitutes an oil reservoir 240, and formed on the shaft 211 is an eccentric 241 on which is mounted a ring 242 pivotally connected at 243 to a plunger 244 of a hydraulic pump. This plunger is reciprocable in the bore of a cylinder 245 mounted within the reservoir chamber, and this pump is adapted to draw oil, through an intake valve 246, into the pump cylinder, and to force the oil under pressure from the pump cylinder, past a discharge valve 247 and through suitable conduits, to the various hydraulic cylinders. The discharge side of the pump is connected, through conduits 248 and 249, to the supply chambers 250 and 251 of the valve boxes 231 and 232. The discharge chambers 253 and 254 of the valve boxes communicate directly with the reservoir chamber. As shown in Fig. 20, the bores of the valves 233 and 238 30 are connected, through the conduits 255 and 256, to the operating cylinders for the high speed friction clutches, and through conduits 257 and 258, to the operating cylinders for the slow speed friction clutches. When the valves 233 and 238 35 are in the position shown in Fig. 20, hydraulic pressure may flow from the supply chambers 250 and 251, through passages on the valves and conduits 255 and 256, to the operating cylinders for the high speed clutches to apply the latter, while the operating cylinders for the low speed clutches are connected to the discharge chambers 253 and 254 through the conduits 257 and 258. When the position of the valves 233 and 238 is reversed, 40 hydraulic pressure may be supplied, through conduits 257 and 258, to the operating cylinders for the low speed clutches to apply the latter, while the operating cylinders for the high speed clutches are connected to the discharge chambers 253 and 254 through the conduits 255 and 256. The 45 release clutches for the drums are connected, through conduits 259 and 260, to the bores of the valves 235 and 236, so that, when the valves are in the position shown in Fig. 20, hydraulic pressure may flow from the supply chambers, 50 through passages on the valves and conduits 259 and 260, to the operating cylinders for the drum release clutches to release the latter. When the position of the valves 235 and 236 is reversed, the operating cylinders for the drum release 55 clutches are connected to discharge chambers through the conduits 259 and 260. The bore for the valve 237 is connected, through conduits 261, to the release cylinder for the bar locking pin, so that, when the valve is in the position 60 70 75

shown in Fig. 20, the bar locking cylinder is connected to the discharge chamber 254 through the conduit 261. When the position of the valve 237 is reversed, hydraulic pressure may flow from the supply chamber 251, through a passage on the valve 237 and conduit 261, to the bar locking cylinder to effect release of the lock. The upper ends of the hydraulic jack cylinders are connected, through conduits 262 and 263, to the bores for the valves 234 and 239, while the lower ends of these cylinders are connected to the valve bores through conduits 264 and 265. When the valves 234 and 239 are in the position shown in Fig. 20, hydraulic pressure may flow from the supply chambers, through the passages on the valves and conduits 264 and 265, to the bottom of one jack and the top of the other, so that one jack is operated while the other is released. When the position of the valves 234 and 239 is reversed, hydraulic pressure may flow from the supply chambers, past the valves and through conduits 262 and 265, to the opposite ends of the jack cylinders. It is obvious that the valves 234 and 239 may be positioned to supply hydraulic pressure to the upper ends of both jack cylinders to effect simultaneous operation of the jacks. Arranged in the pump cylinder is an automatic by-pass valve 266 for automatically connecting the discharge side of the pump to the oil chamber when the hydraulic system is overloaded, while located adjacent the other valve box 232 is a by-pass control valve 267 having a manual operating plunger 268 so that the operator may readily control the pressure in the hydraulic system. It is accordingly evident that the fast and slow speed friction clutches, the drum release clutches, the bar lock and the machine tilting jacks are all hydraulically controlled, and, due to the arrangement of the control valves in the convenient location at the operator's end of the machine, control of the various devices is greatly facilitated.

The cables of the cable winding drums 166 and 167 may be extended from the machine in various manners to effect maneuvering and feeding of the machine and to swing the kerf cutter about its pivot. Arranged on vertical axes at the opposite corners of the feed casing, at the end of the machine remote from the cutting mechanism, are horizontal guide rolls 269 and 270, while journaled on an upstanding axis on a detachable bracket 271 is a horizontal guide roll 272. To permit attachment of the guide roll 272 to the machine, the bracket 271 is formed with a longitudinal guide 273 receivable in a longitudinal guideway 274 formed within the adjacent side of the motor frame section 163. A similar guide roll and bracket may be attached to the opposite side of the machine, and the opposite side of the motor frame section is provided with a similar guideway 275 to receive the bracket. The operator, by grasping the guide roll bracket 271, may slide the latter outwardly from the guideway in a direction towards the cutter bar to release the bracket from the machine casing and, obviously, the guide roll may be attached to the machine by sliding the guide of the bracket in the opposite direction in the guideway 275. The opposite sides of the machine casing are formed with curved guiding surfaces 276 and 277 so that either cable may be extended from its winding drum along the side of the machine, the cable sliding along these curved guiding surfaces as it is wound in by its drum. As in the embodiment of the invention

above described, the cutter bar hanger frame has formed thereon an arcuate cable guiding groove 278, while formed at the opposite sides of the vertical frame portion 199 of the hanger frame are hook-shaped portions 279 to which eye members 280, fixed to the free ends of the cables, are connectible. Either of the cables may be extended from its winding drum along the sides of the machine casing about the guiding groove 278 on the hanger frame into connection with a hook-shaped portion 279 and, when the bar lock is released, and the cable is wound in by its drum, the cutter bar may be swung about its pivot relative to the machine casing. One cable may be employed for effecting cutter bar swing in one direction and the other cable to effect cutter bar swing in the opposite direction. When the cutter bar is swung into its desired angular position with respect to the machine casing, it may be locked to the casing by the locking pin 203.

The general mode of operation of this illustrative embodiment of the improved mining machine will be clearly apparent from the description given. The cables 168 and 169 may be extended in various directions from the machine about the guides so as to enable the machine to operate as either a room and pillar or longwall machine in accordance with either the room and pillar or longwall system of mining in the manner well understood by those skilled in the art. The cable 168 may be extended from the drum 166 around the rear guide 270 and laterally from the machine to an anchor jack located at the left hand rib, while the cable 169 may be extended from the drum 167, around the front guide 268, along the side of the machine casing and around the guide roll 272, and laterally from the machine to an anchor jack located at the right hand rib, and the machine may then be sumped in, fed transversely across the face, and withdrawn from the face in accordance with the room and pillar system of cutting. Either of the cables 168 and 169 may be extended along the side of the machine, around the guiding groove 278 on the bar hanger frame, into connection with one of the hook-shaped portions 279, so that, when the cable is wound in, the cutter bar may be swung about its pivot to effect sumping of the cutter bar beneath the coal in accordance with the longwall system of cutting, and either cable may be extended from its drum to an anchor jack located at the coal face in advance of the machine, so that, when the cable is wound in, the machine is fed bodily along the coal face. By operating the tilting jacks, the machine may be tilted about transverse and longitudinal axes to vary the angle in altitude of the kerf cutter during either system of cutting. The machine is readily reversible simply by reversing the motor, rearranging the cables on the drums and reversing the cutting elements of the cutter chain.

In the illustrative embodiment of the invention shown in Figs. 21 to 27 inclusive, the machine is essentially the same as that disclosed in Fig. 1, with the exception that mechanical controls for the various clutches and bar lock are afforded, and a slightly different form of bar swinging means is employed. In this illustrative construction, the mining machine generally comprises a low compact casing 285, similar to the casing of the machine shown in Fig. 1, having a smooth bottom surface 286 and adapted to rest upon and slide in any direction over the mine floor. The machine casing comprises a motor frame section 70

287, a feed and cutter frame section 288 and a guide frame section 289, and these casing sections are rigidly united together in any suitable manner. Arranged within a transverse horizontal 5 chamber 290, extending across the bottom portion of the frame section 288 in a transverse zone between the forward end of the motor frame section and a kerf cutter 291, are relatively rotatable feed operating and controlling members, 10 herein in the form of cable winding drums 292 and 293, having respectively wound thereon feeding and controlling cables 294 and 295 respectively. The kerf cutter 291 projects horizontally from the machine casing section 288 and comprises an 15 elongated, horizontal, plane cutter bar 296 having mounted for circulation about its margin an endless cutter chain 297.

The driving means and pivotal mounting structure for the kerf cutter are essentially the same 20 as those described above in the illustrative embodiment of the invention disclosed in Figs. 1 to 10 inclusive, and similar parts are, in this instance, designated by the same reference characters. The cutter chain is driven from the motor 25 in the casing section 287, through a spur motor pinion 13 formed integral with the motor power shaft 12 and meshing with the spur gear 14 (see Fig. 23) keyed to the horizontal longitudinally 30 extending shaft 15. The shaft 15 is arranged parallel with and in horizontal planes above the motor power shaft, and suitably journaled within the casing section 288. Keyed to and driven by the shaft 15, is the bevel gear 16 meshing with the horizontal bevel gear 17 and having its hub 35 journaled on bearing sleeves supported by the clutch sleeve 18 keyed to a vertical shaft 298. As illustrated, the casing section 288 is provided, at one end thereof, with a projecting bearing frame and gear housing 299 of partially cylindrical shape and providing a housing for the bevel 40 gearing 16 and 17, and the vertical shaft 298 is journaled on this frame portion 288. The upper portion of the bearing frame is provided with an upstanding circular bearing support 300, while 45 depending from the lower portion of the frame is a circular bearing support 301; and the shaft 298 is journaled in ball bearings arranged within these bearing supports. Formed on the hub of the bevel gear 17 are the clutch teeth 22 connectible, by the sliding clutch member 24, to the 50 clutch teeth 25 formed on the clutch sleeve 18. The operating means for the clutch 24 is the same as that shown in Fig. 1, and therefore a description of the same is not deemed necessary. 55 Keyed to and driven by the shaft 298, is a chain sprocket 302 engaging and driving the endless cutter chain 297 of the kerf cutter. It will thus be seen that, when the clutch 24 is connected, the cutter chain 297 may be driven from the motor 60 power shaft, spur gears 13, 14, shaft 15, bevel gear 16, 17 and the vertical shaft 298; and, when the clutch 24 is disconnected, the cutter chain may remain idle during running of the motor. 65 The pivotal mounting for the kerf cutter 291 65 comprises a hanger frame 303 having a cylindrical bearing support 304 journaled on a bearing sleeve supported by the cylindrical bearing support 301. Formed integral with the hanger frame is an upstanding frame portion 305 having secured thereto a bearing frame 306 overlying the upper portion of the frame portion 299 of the casing section 288 and journaled on bearing sleeves supported by the cylindrical bearing support 306. 70 75 The feeding and guiding means for the ma-

chine is generally similar to that disclosed in the embodiment of the invention shown in Figs. 1 to 10 inclusive, and the same reference characters designate the similar parts. As in the other forms of the invention, the worm wheels 5 coaxial with the drums constitute the high speed terminal driving elements and the large spur gears coaxial with the drums constitute the low speed terminal driving elements, the high and low speed drives including friction controlling 10 clutches for selectively connecting the drums in driving relation with the fast and slow speed terminal driving elements. Further illustration and description of the drum release clutches and the high and low speed driving elements are not 15 considered necessary, since they have been previously described and illustrated. There are, however, in this instance, no retarding frictions for the drums.

Now referring to the improved control means 20 for the various friction clutches, the drum release clutches, and the bar lock, it will be noted that threaded within nuts 307 secured within the casing section are vertical screws 308 engaging the upper race 119 of the ball thrust 25 bearing 111. The lower bearing race 112 engages the plungers 113, in turn engaging the pressure ring 114 for the discs of the clutch. Formed integral with the screws are spur gears 309 meshing with the teeth of a rack 310. This 30 rack is mounted within a longitudinal guideway 311 formed within a guide frame 312 suitably secured within the casing section 288. Secured to the end of this rack is an abutment member 313 secured to a tubular rod 314 guided on the 35 top of the motor casing section 287 and pivotally connected at 315 to a link 316, in turn pivotally connected at 317 to a horizontally swingable lever 318. When the levers 318 are swung about their pivots to move the rods 314 axially, the 40 racks 313, 316 are moved simultaneously within their guideways to rotate the spur gears 309, and as a result the screws 308 are moved axially to apply loading pressure to the high speed disc 45 clutches. The drum release clutches 66 are operated by means of vertical rods 319 guided within the vertical bores in the shafts 59 and 60 and engaging at their lower ends transverse pins 320 guided for movement in vertical slots 321 in the shafts and connected to the shipper member 322 for the clutch member 66. Mounted for reciprocation in longitudinal guideways 323 in the guide frames 312 and longitudinal guide slots 324 in the racks are wedge blocks 325 having inclined surfaces engageable with the upper 50 ends of the rods 319, and secured to these wedge blocks are rods 326 extending axially through the tubular shafts 314 and having their ends each connected by a pin and slot connection 327 to an operating lever 328. It will thus be seen 55 that when the operator swings the lever 328, the rods 326 are moved axially within the tubular rods 314, thereby moving the wedge blocks within their guideways, the inclined wedge surfaces on the wedge blocks engaging the upper ends 60 of the vertical shafts 319 to depress the latter, thereby moving the pins 320 downwardly within their slots to move the shipper members 322 into a position to release the drum clutches 66. The operating means for the low speed clutches 70 48 and 49 comprises, as shown in Fig. 25, spur gears 330 also meshing with the teeth of the rack 310 (see also Fig. 21), and these gears are formed integral with vertical screws 331 threaded within stationary nuts 332 and engaging an 75

- annular plate 333. This plate engages the upper race of the ball thrust bearing 104, and the lower bearing race in turn engages the plungers 122 secured to the pressure plate 123 for the 5 clutch discs. The operating means for the low speed clutches are so coordinated with the high speed clutch operating means that, when the high speed clutches are applied, the low speed clutches are always released, and vice versa.
- 10 When the levers 318 are swung about their pivots to slide the racks 310 within their guideways, the gears 330 are rotated, moving the screws axially downwardly, thereby depressing the annular plates 333 to load the clutch discs.
- 15 When the racks are moved in the opposite direction, the low speed clutches are, of course, released.

The locking means for the kerf cutter comprises an arcuate flange 335, herein formed integral with the bearing frame 306, and the outer edge of this flange is formed with gear teeth 336 with which projecting teeth 337 formed on a reciprocable locking block 338 are engageable. This locking block is guided in a longitudinal 20 guideway 339 formed in the upper portion of the casing section 288. Extending longitudinally within the upper portion of the machine casing is an operating rod 340 having formed thereon screw threads 341 threadedly engaging a stationary nut 342 secured within the upper portion of the casing section. This rod has a circular button 343 mounted in a vertical key slot 344 in the locking block 338 so that as the rod is moved axially the locking block moves therewith, while rotation of the rod with respect to the block is permitted. The operating rod 340 has an operating lever 345. When the rod is rotated, the screw threads impart axial movement thereto, thereby reciprocating the locking block into and out of locking relation with respect to the teeth on the bearing support flange.

As mentioned above, the cable winding drums 292 and 293 are arranged within the transverse chamber 290 in a transverse zone between the 45 motor and the kerf cutter, and the cables 294 and 295 wound on these drums are adapted to be extended from the machine in various manners to effect feeding and guiding of the machine and to swing the kerf cutter about its pivot. In addition to the guide rolls 145, 146, 147, 149 and 150 are vertical guide rolls 346 arranged in coaxial relation on horizontal axes arranged parallel with and above the axes of the guide rolls 147, and horizontal guide rolls 50 347 arranged at the opposite sides of the cutter and feed frame section. Formed on the bearing support 306 of the hanger frame 303 for the kerf cutter are projections 348 to which eye members 349, fixed to the free ends of the 55 cables, are connectible. Either of the cables may be extended from its winding drum around the guide rolls 147 upwardly around the guide rolls 346 and then along the sides of the machine frame near the top of the latter and around the 60 guide rolls 347 into connection with the projections 348, and when the bar lock is released and the cable is wound in by its drum, the cutter bar may be swung about its pivot relative to the machine casing. One cable may be employed 65 for effecting cutter bar swing in one direction and the other cable to effect cutter bar swing in the opposite direction.

The general mode of operation of this improved mining machine is as follows: The cables 70 75 294 and 295 may be extended in various direc-

tions from the machine about the guide rolls 145, 146, 147, 149, 150 and 346. Either of the cables may be extended from the drums 292 and 293 into connection with the cutter bar, and the cutter bar swung in either of opposite directions 5 about its pivot at either a relatively high or a relatively low speed. Either of the cables may be extended from the winding drums around the guide rolls laterally from the sides of the machine to a suitable anchor jack located at the rib 10 so that, when the cable is wound in, the machine may be fed bodily along the coal face. During cutting in accordance with the room and pillar system of mining, the cable 294 is extended from the drum 295 around the guide 15 sheave 150 and laterally from the machine to an anchor jack located at the left hand rib, while the cable 295 is extended from the winding drum 293 around the forward guiding roll 145 and laterally from the machine to an anchor 20 jack located at the right hand rib. The machine may then be dumped in and fed transversely across the face and withdrawn from the coal in the usual manner. During cutting in accordance with the longwall system of mining, the 25 cable 295 may be connected to the cutter bar and the cutter bar swung about its pivot to effect the sumping cut beneath the coal. The cutter bar is then locked in its right angle position with respect to the machine casing, and the 30 feed cable is extended from the feeding drum forwardly along the coal face to an anchor jack located at the face in advance of the machine; and, when the cable is wound in, the machine is fed bodily along the coal face. The machine may 35 be reversed simply by reversing the motor, rearranging the cables on the drums and reversing the cutting elements of the cutting chain.

As a result of this invention, it will be noted that an improved coal mining machine of the 40 combined room and pillar and longwall floor cutter type is provided having improved feeding and cutting mechanisms whereby the coal may be cut in a more efficient manner. It will further be noted that in all forms of the invention, 45 an improved arrangement of the feeding and controlling drums and improved driving means for the drums are provided. It also will be noted that in the first two embodiments of the invention improved hydraulic operating means for the 50 various clutches, the retarding frictions, the bar lock, and machine tilting jacks are provided, while in the third embodiment of the invention, there are provided improved mechanically actuated means for the clutches and bar lock. 55 It will further be evident that by the provision of the improved transmission mechanism the feed operating and controlling drums may be driven in an improved manner, while at the same time the machine is rendered extremely compact. 60 These and other uses and advantages of the various forms of the improved mining machine will be clearly apparent to those skilled in the art.

While there are in this application specifically 65 described several forms which the invention may assume in practice, it will be understood that these forms of the same are shown for purposes of illustration, and that the invention may be further modified and embodied in various other 70 forms without departing from its spirit or the scope of the appended claims.

What we claim as new and desire to secure by Letters Patent is:

1. In a mining machine transmission mecha- 75

- nism, in combination, relatively rotatable members to be driven, and motor operated driving means for rotating said members at high and low speeds including a fast speed gear train and a low speed gear train said gear trains including high and low speed terminal gears arranged coaxially with said members, said low speed gear trains including gears coaxial with and driven by said high speed terminal gears, gears meshing with said last mentioned gears and rotating on axes parallel with the axes of said members, gears coaxial with said last mentioned gears and driven thereby and meshing with said low speed terminal gears, and friction clutches coaxial with said gears which mesh with said low speed terminal gears for effecting connection of said low speed gear trains in driving relation with said members.
2. In a mining machine transmission mechanism, in combination, relatively rotatable members to be driven, and motor operated driving means for rotating said members at high and low speeds including a fast speed gear train and a low speed gear train, said gear trains including high and low speed terminal gears arranged coaxially with said members, said low speed gear trains including gears coaxial with and driven by said high speed terminal gears, gears meshing with said last mentioned gears and rotating on axes parallel with the axes of said members, gears coaxial with said last mentioned gears and driven thereby and meshing with said low speed terminal gears, friction clutches coaxial with said high speed terminal gears for connecting the high speed gear trains in driving relation with said members, and friction clutches coaxial with said gears which mesh with said low speed terminal gears for effecting connection of the low speed gear trains in driving relation with said members.
3. In a mining machine feeding mechanism, relatively rotatable feed operating and controlling members adapted to cooperate directly with flexible feeding means, and motor operated feeding means for rotating said members at high or low speeds including for each member a fast speed gear train and a low speed gear train, said gear trains including high and low speed terminal gears arranged coaxially with said members, and frictional resistance mechanisms for frictionally resisting rotation of said members when drive of said members through said gear trains is interrupted including friction brakes and gears respectively controlled by said brakes and meshing with said low speed terminal gears.
4. In a mining machine transmission mechanism, in combination, a member to be driven, a fast speed gear train including a fast speed terminal gear coaxial with said member, a slow speed gear train including a slow speed terminal gear coaxial with and connected to said member, a gear meshing with and driving said slow speed terminal gear, a gear coaxial with said third mentioned gear, a clutch for connecting said fast speed terminal gear to said member to be driven, and a clutch for connecting said third mentioned gear to said fourth mentioned gear for driving thereby.
5. In a mining machine transmission mechanism, in combination, a member to be driven, a fast speed gear train including a fast speed terminal gear coaxial with said member, a slow speed gear train including a slow speed terminal gear coaxial with said member, a clutch for connecting said slow speed terminal gear to said member,

a gear meshing with and driving said slow speed terminal gear, a gear coaxial with said third mentioned gear, a clutch for connecting said fast speed terminal gear to said member to be driven, and a clutch for connecting said third mentioned gear to said fourth mentioned gear for driving thereby.

6. In a mining machine transmission mechanism, in combination, a member to be driven, a fast speed gear train including a fast speed terminal gear coaxial with said member, a slow speed gear train including a slow speed terminal gear coaxial with said member, a clutch for connecting said slow speed terminal gear to said member, a gear meshing with and driving said slow speed terminal gear, a gear coaxial with said third mentioned gear, a clutch for connecting said fast speed terminal gear to said member to be driven, a clutch for connecting said third mentioned gear to said fourth mentioned gear for driving thereby, and a frictionally controlled retarding gear meshing with said slow speed terminal gear for resisting rotation of the latter when said third mentioned clutch is released.

7. In a mining machine transmission mechanism, in combination, a member to be driven, fast and slow speed gear trains including fast and slow speed terminal gears coaxial with said member to be driven, clutches for connecting said gear trains in driving relation with said member to be driven, and a frictionally controlled retarding gear meshing with said slow speed terminal gear for resisting rotation of the latter when said slow speed gear train clutch is released.

8. In a mining machine transmission mechanism, in combination, a member to be driven, a high speed gear train comprising a high speed terminal gear coaxial with said member, a low speed gear train driven by said high speed terminal gear and including a low speed terminal gear coaxial with said high speed terminal gear, and a gear meshing with said low speed terminal gear and arranged on a parallel axis, said low speed terminal gear connected to said member to be driven, a driving element coaxial with said third mentioned gear, a clutch coaxial with said high speed terminal gear for connecting the latter to said member to be driven, and a clutch coaxial with said third mentioned gear for connecting the latter to said driving element.

9. In a mining machine transmission mechanism, in combination, a member to be driven, a high speed gear train comprising a worm and a worm wheel meshing therewith and driven thereby, said worm wheel constituting the high speed terminal element of said gear train and arranged coaxial with said member to be driven, a low speed gear train comprising a spur gear coaxial with and driven by said worm wheel, a spur gear meshing with said first mentioned spur gear and driven thereby, a third spur gear coaxial with and driven by said second mentioned spur gear, and a fourth spur gear coaxial with and connected to said member to be driven, said fourth mentioned spur gear driven by said third mentioned spur gear and said fourth mentioned spur gear constituting the low speed terminal element of said low speed gear train.

10. In a mining machine transmission mechanism, in combination, a member to be driven, a high speed gear train comprising a worm and a worm wheel meshing therewith and driven thereby, said worm wheel constituting the high speed terminal element of said gear train and arranged coaxial with said member to be driven, a low speed gear train comprising a spur gear coaxial with

and driven by said worm wheel, a spur gear meshing with said first mentioned spur gear and driven thereby, a third spur gear coaxial with and driven by said second mentioned spur gear, and a fourth spur gear coaxial with and connected to said member to be driven, said fourth mentioned spur gear driven by said third mentioned spur gear and said fourth mentioned spur gear constituting the low speed terminal element of said low speed gear train, and a frictionally controlled retarding gear meshing with said low speed terminal gear for resisting rotation of the latter.

11. In a mining machine transmission mechanism, in combination, a member to be driven, a high speed gear train comprising a worm, a worm wheel meshing therewith and driven thereby, said worm wheel constituting the high speed terminal element of said gear train and arranged coaxially with said member to be driven, a low speed gear train comprising a spur gear coaxial with and driven by said worm wheel, a spur gear meshing with said first mentioned spur gear and driven thereby, a third spur gear coaxial with and driven by said second mentioned spur gear, and a fourth spur gear coaxial with and connected to said member, said fourth mentioned spur gear driven by said third mentioned spur gear and constituting the low speed terminal element of said low speed gear train, a clutch coaxial with said worm wheel for connecting the latter to the member to be driven, and a clutch coaxial with said third mentioned spur gear for connecting the latter to said second mentioned spur gear for driving thereby.

12. In a mining machine transmission mechanism, in combination, a member to be driven, a high speed gear train comprising a worm, a worm wheel meshing therewith and driven thereby, said worm wheel constituting the high speed terminal element of said gear train and arranged coaxially with said member to be driven, a low speed gear train comprising a spur gear coaxial with and driven by said worm wheel, a spur gear meshing with said first mentioned spur gear and driven thereby, a third spur gear coaxial with and driven by said second mentioned spur gear, and a fourth spur gear coaxial with and connected to said member, said fourth mentioned spur gear driven by said third mentioned spur gear and constituting the low speed terminal element of said low speed gear train, a clutch coaxial with said worm wheel for connecting the latter to the member to be

driven, a clutch coaxial with said third mentioned spur gear for connecting the latter to said second mentioned spur gear for driving thereby, and a frictionally controlled retarding gear meshing with said fourth mentioned spur gear for resisting rotation of said member when said last mentioned clutch is released.

13. In a mining machine transmission mechanism, in combination, a member to be driven arranged on a vertical axis, a fast speed gear train including a terminal gear coaxial with said member, a slow speed gear train including a terminal gear coaxial with and connected to said member, a gear meshing with and driving said slow speed terminal gear, a gear coaxial with said third mentioned gear, a clutch for connecting said fast speed terminal gear to said member to be driven, and a clutch for connecting said third mentioned gear to said fourth mentioned gear for driving thereby.

14. In a mining machine transmission mechanism, in combination, a member to be driven arranged on a vertical axis, a fast speed gear train including a terminal gear coaxial with said member, a slow speed gear train including a terminal gear coaxial with said member, a clutch for connecting said slow speed terminal gear to said member, a gear meshing with and driving said slow speed terminal gear, a gear coaxial with said last mentioned gear, a clutch for connecting said fast speed terminal gear to said member to be driven, and a clutch for connecting said third mentioned gear to said fourth mentioned gear for driving thereby.

15. In a mining machine transmission mechanism, in combination, a member to be driven arranged on a vertical axis, a fast speed gear train including a terminal gear coaxial with said member, a slow speed gear train including a terminal gear coaxial with said member, a clutch for connecting said slow speed terminal gear to said member, a gear meshing with and driving said slow speed terminal gear, a gear coaxial with said last mentioned gear, a clutch for connecting said fast speed terminal gear to said member to be driven, a clutch for connecting said third mentioned gear to said fourth mentioned gear for driving thereby, and a frictionally controlled retarding gear meshing with said slow speed terminal gear for resisting rotation of the latter when said third mentioned clutch is released.

JOSEPH F. JOY.
CLYDE P. BALDWIN.

CERTIFICATE OF CORRECTION.

Patent No. 2,211,781.

August 20, 1940.

JOSEPH F. JOY, ET AL.

It is hereby certified that error appears in the printed specification of the above numbered patent requiring correction as follows: Page 4, first column, line 57, for the word "point" read --joint--; page 5, first column, line 25, beginning with "As previously mentioned" strike out all to and including "later described." in line 32, second column, same page, and insert the same on page 6, second column, between lines 10 and 11; page 6, first column, line 16, for the reference numeral "78" read --178--; page 10, first column, line 5, claim 1, after "train" insert a comma; and that the said Letters Patent should be read with this correction therein that the same may conform to the record of the case in the Patent Office.

Signed and sealed this 8th day of October, A. D. 1940.

(Seal)

Henry Van Arsdale,
Acting Commissioner of Patents.
